UNITED STATES PATENT OFFICE

CHARLES L. RAYFIELD, OF CHICAGO, ILLINOIS

SAFETY SWITCH FOR OIL BURNERS

Application filed August 10, 1927. Serial No. 211,884.

This invention relates to a control for oil burning systems and concerns itself with means for preventing the restarting of the motor until the furnace has cooled off and means for stopping the motor if the fuel does not ignite within a predetermined time.

The invention comprises the novel structure and combinations hereinafter described and more particularly pointed out and defined in the appended claims.

In the accompanying drawings which illustrate a preferred embodiment of this invention and in which similar reference numerals refer to similar features in the different views, 15 Figure 1 is a diagrammatic view illustrating the system in which this invention is incorporated, the parts being shown in idle positions.

Figure 2 is an enlarged sectional view of a 20 safety switch taken upon the line II—II of Figure 3, for stopping the motor if the fuel does not initially ignite within a predetermined time.

Figure 3 is an enlarged plan view of the 25 switch.

Figure 4 is an enlarged side view of the furnace thermostat and switch.

Figure 5 is an enlarged end view of the 30 furnace thermostatic switch.

Figure 6 is a sectional view upon the line 35 VI—VI of Figure 4.

Figure 7 is a view of the safety switch shown in Figure 2.

Figure 8 is an end view of the safety switch. 40

Figure 9 is a fragmentary part sectional view of the furnace thermostat and switch illustrating the frictional connection therebetween.

In Figure 1 of the drawing, there is illustrated in diagrammatic form a well known regulating system in which this invention was incorporated. In order that this invention and its relation in the system and its purpose 45 may be readily understood, a brief description of the system with the invention incorporated therein as shown in Figure 1 will be given. In referring to said Figure 1, the wires L designate the 110 volt line that supplies the current for the system. The wires M lead to the motor. The wires L are adapt-

ed to be connected with the wires M of the motor circuit through a relay armature or switch 1. The wires L also connect with a transformer 2. One of the induction coils on one side of this transformer is electrically connected by means of a wire 3 to a relay coil 4 that is adapted when energized for attracting the armature 1 and closing the motor circuit. The relay coil 4 is connected by means of a conductor 5 with a secondary transformer circuit 6 which in turn is connected to a contact 7 of the furnace thermostatic switch. The current from the contact 7 returns through a switch member 8 to the second contact 9 of the furnace switch and from there through a conductor 10 to the boiler control 11 and from the boiler control, the current emerges through a conductor 12 to the room thermostat 13. From the thermostat 13 the current passes through a conductor 14 to a safety switch 15 which is normally closed but which may be opened by the coils 36 in the aforementioned secondary transformer circuit 6 as will be later more fully explained.

From the switch 15, the current returns through a conductor 17 connected to a conductor block 18 from which the current emerges through a conductor 19 to the other coil or side of the transformer. The circuit just described is the starting circuit for the system. It will of course be understood that the furnace switch, the room thermostat and boiler control are all closed when the system is idle or the parts are cooled to a sufficient degree.

The running circuit of the system will now be described. It will be noted that a holding contact 20 is supported upon an arm extending from the switch member 1. When the motor switch 1 is closed, the holding contact 20 is put in contact with a terminal 21 of the running circuit 22 which leads to the boiler control 11 and from thence to the room thermostat 13. From the room thermostat, the circuit traverses the conductors 14, 17, and 19, to one side of the transformer 2. This running circuit is completed through the conductor 3, relay 4, and holding contact 20, which is connected through its arm to the relay coil.

The structure of the safety switch and furnace switch will now be described. The safety switch is shown in Figures 2, 3, 7 and 8, and in referring to said figures, it will be noted that the switch comprises a support 23 having a switch member 24 of Z-shape, one flange of which is secured by a post 25 to the bottom of the supports 23. The other flange forms a contact for one end of a switch member 26. The other end of this switch member is upwardly offset and this offset portion is attached to the support 23 by a post 27. Adjacent this offset portion of said switch member, a bracket 28 is secured to the switch member 26 and depends therefrom. The depending part of this bracket is provided with a central slot 29 (Figure 8) and lateral notches 30 adjacent said slot.

20 The end of the support 23 opposite the bracket 28 is provided with a depending block or portion 31 to the bottom of which a thermostatic element bar 32 is secured by a suitable screw 33. The forward end of this 25 thermostatic element is so fashioned as to provide a tongue 34 that extends through the slot 29 and lateral tines 35 that are located in the notches 30. Suitable heating coils 36 extend lengthwise of the thermostatic bar 32. 30 These coils are connected with the binding posts 37 on the support 23 by means of conductors 38.

A cap plate 39 is secured upon a central boss 40 upon the top of the support 23. This 35 boss is provided with a socket 41 through which a plunger 42 passes that is adapted for engaging the switch member 26. A coil spring 43 in said socket normally bears against a collar 44 on the plunger 42 for elevating the same above the switch member 26. 40 The plunger may be manually operated to move the switch member 26 to closed position.

The furnace thermostat which will now be described is illustrated in Figures 4, 5, 6, and 45 9. In referring to said figures, especially Figure 4, it will be noted I have illustrated a furnace wall or door 45 to which a U-shaped thermostatic element 46 is attached by one of the branches or arms thereof. The other arm 50 thereof extends into a notch 47 in the under-side of a switch operated bar 48 which slidably extends through the furnace wall and through a switch casing 49 attached in spaced relation to the furnace wall. The outer end 55 of the rod 48 is hollow as shown in Figure 9. A second rod 50 telescopes within the hollow portion of the rod 48 and is frictionally retained by a set screw 51 which is sustained in a small barrel or sleeve 52 attached to the 60 rod 48. This frictional connection provides a certain amount of yield. The rod 50 slidably extends through the switch housing 49 and has affixed upon its outer end a cross-head 54 which carries a pair of adjustable 65 studs 55. The crosshead 54 is provided with a

depending lug 56 which has a guide aperture for receiving a guide stud or screw 57 extending from an insulated plate 58 that closes the adjacent side of the casing. Upon the face of the plate 58 are a pair of resilient switch members 59 which are secured at their lower ends upon posts 60 which extend through the plate 58. Each upper end of the switch members 59 is provided with a contact point or pin 61 which is adapted to form a connection with a contact post 62 extending through the plate 58. The switch members 59 lie under the studs 55 on the crosshead 54 for movement thereby as will later more fully appear.

As shown in Figure 6, a pair of electrical conductors 63, are respectively connected to the posts 60 within the housing 49 and a pair of electrical conductors 64 are connected to one post 62 while the other post 62 is connected by a conductor 65 with the diagonally opposite post 60.

The operation of this system will now be described. As soon as the current is turned on the relay 4 will attract the armature 1 and close the starting circuit which traverses the furnace switch which is closed when the furnace is cooled off. At the same time the current will also flow through the heating coils 36 of the safety switch. Now if the fuel should not ignite and start the furnace to heat the same sufficiently for actuating the thermostat 46 for moving the bar 48 for breaking the circuit through the furnace thermostatic switch in a predetermined time, the coils 36 will have heated the thermostatic bar 32 which will flex for actuating the switch member 26 for opening the switch and stopping the motor.

However, if the fuel is properly ignited when the motor is started, the furnace will be sufficiently heated to actuate the thermostatic bar 46 to move the bar 48 in a direction away from the furnace for opening the furnace thermostatic switch before the coils 36 are heated for opening the safety switch. When the furnace thermostatic switch is open, the current through the safety switch is, of course, cut off.

Obviously, when the furnace is functioning, the furnace thermostatic switch is open and it will be maintained in open position as long as the furnace is sufficiently hot. Now if the boiler or room thermostat should get in condition for opening the running circuit of the motor, for stopping the motor the armature 1 would drop down by gravity. Then, before the system can start up again, it will be necessary for the furnace to cool sufficiently to cause the thermostat 46 to actuate the bar 48 for closing the furnace thermostatic switch before the starting current can function again. Consequently, a safeguard against starting the system when the furnace is hot has been provided whereby

explosions and the like are prevented in the furnace.

I am aware that numerous details of construction may be varied through a wide range without departing from the principles of this invention, and I therefore do not purpose limiting the patent granted otherwise than necessitated by the prior art.

I claim as my invention:

- 10 1. In combination, a supporting wall, a switch supporting frame, a hollow bar slideable on said wall, a thermostat connected with said bar to control the sliding movement thereof, a rod slideable on said frame and extending at its inner end into said hollow bar, switch mechanism on said frame controlled by the movement of said rod, and adjustable pressure means carried by said bar and pressing said rod into frictional engagement with said bar whereby movement of said switch mechanism by said thermostat will be transmitted through the frictional connection of said bar and rod.
- 15 2. In thermostatically controlled switch mechanism, the combination of an actuating bar structure comprising two members telescopically connected together for relative movement, a thermostat connected with the end of one of said members, switch controlling mechanism connected with the end of the other member, a barrel on one of said members having an adjustable spring pressed plunger therein engaging the other member whereby actuation of the switch
- 20 mechanism by said thermostat will be through the resistance connection of said member.
- 25 3. In testimony whereof I have hereunto subscribed my name at Chicago, Cook county, Illinois.

CHARLES L. RAYFIELD.
